UNITED STATES PATENT OFFICE.

JOHN H. NICHOLSON, OF PITTSBURG, PENNSYLVANIA, ASSIGNOR TO NATIONAL TUBE COMPANY, OF PITTSBURG, PENNSYLVANIA, A CORPORATION OF NEW JERSEY

METHOD OF MAKING SEAMLESS TUBING.

No. 870,246.

Specification of Letters Patent.

Patented Nov. 5, 1907.

Application filed December 15, 1904. Serial No. 237,012.

To all whom it may concern:

Be it known that I, JOHN H. NICHOLSON, of Pittsburg, Allegheny county, Pennsylvania, have invented a new and useful Method of Making Seamless Tubing, 5 of which the following is a full, clear, and exact description, reference being had to the accompanying drawings, forming part of this specification, in which the figure is a plan view of apparatus arranged to carry out my invention.

10 Heretofore in the manufacture of hot-rolled blanks from pierced billets for the purpose of cold drawing, a plug mill of the well-known type is one of the common devices that has been used; the hollow billet is elongated in this mill and the thickness of its wall reduced 15 to a sufficient gage or thinness, so that the same can be cold-drawn with smooth surfaces to the desired thickness of wall. In this plug mill operation it is desirable to produce hot-rolled blanks, or tubes, as round and as smooth on the inside as possible, to facilitate the cold-drawing and enable the tube to be finished to the desired gage and to smooth-finish it in as few cold-drawing 20 passes as possible. Heavy reductions cannot be taken on the cold draw bench, without excessive breakage, until the rolled blank has been rounded up and the interior 25 scratches removed, owing to the tendency of the metal to pick up, or accumulate, ahead of the mandrel during the cold-drawing. To partly overcome this difficulty, the rolled blanks are given several additional passes on the plug-mill for the purpose of rounding 30 up the diameter and smoothing the interior surface, little or no work being done in reducing the thickness of wall during such additional passes. This additional work for the plug-mill occupies much time, and reduces the output of the mill.

35 My invention is designed to overcome this difficulty, so that the plug-mill may be used for its normal function of reducing the thickness and elongating the blank, without giving further passes on such mill for rounding up and working out the scratches, thereby reducing the

40 number of passes that have been heretofore deemed necessary in the production of hot-rolled blanks, suitable for cold-drawing. For this purpose I subject the blank to a new operation, intermediate between the plug-mill and the draw-bench. In this additional step

45 I pass the rolled blank through a reeling, or cross-rolling machine, in which the blank is rounded up, its interior and exterior surfaces smoothed, and the scratches practically eliminated, giving a much better blank or tube for cold-drawing than could be produced on the 50 plug-mill, no matter how many additional passes for rounding and smoothing were given.

In addition to increasing the output of the plug-mill by using this new and intermediate operation, it reduces the number of passes heretofore required on the 55 cold draw bench, as the reeled tube is round and

smooth, and a heavy draft, or pull, can be taken in the first pass over the bench, without fear of excessive breakage. This is not possible under the old method of operating, as the first pass over the bench is mainly used to round up the billet and smooth out the interior 60 scratches.

In the drawings, in which I show one form of apparatus for carrying out my invention, 2 indicates a plug-mill which is preferably of the type shown in the patent to myself and R. C. Stiefel No. 770,195, dated September 13th, 1904, having a driving connection 3 arranged to drive a pair of rolls continuously in the same direction. The upper roll is vertically movable in its housing to provide for separating the rolls sufficiently for the return feeding of the tube. The means for moving the upper rolls may be of any desirable type, such for example as shown in our patent above referred to.

On the feeding side of the rolls is a feed-trough 4 mounted on supports movable on transverse tracks 5 to bring the table into line with any of the roll 75 passes.

On the delivery side of the rolls are rods 6 which are fixed at the rear end and extend through suitable supports to the respective roll passes, being formed at their ends to receive the mandrel plugs over which the tubes 80 are rolled. The tubes are stripped from the rods and returned to the feeding side in the same axial line as that of the delivery, by suitable mechanism, such as shown in our patent, the blank being thus fed forwardly into the bite of the rolls and rolled over one of the plugs 85 and rods. The mandrel plug is then removed, the rolls are moved apart, and the blank is stripped backwardly over the mandrel rod in the same line, moving backwardly through the pass. The mandrel plug is then replaced, the rolls are brought more closely together than 90 in the previous rolling, and the operation is repeated. The plug rolling may be completed in the same pass, or in successive passes.

The plug-mill shown and described is not essential to my invention as the pierced billets may be taken directly to the reeling mill in making heavy gages. Any desirable type of plug-mill may be used, though I prefer the one shown, since its operation is so rapid that the blank may be reduced sufficiently for drawing, before the metal has become too cold.

•After the plug-mill rolling is completed the tube is returned to the feeding side and rolls down over inclined skidways 7 upon feeding rollers 8. These rollers may be driven by bevel-gear connection with the shaft 9, driven from the motor 10. This roller table 105 feeds the hot tube forwardly to the reeling mill 11. This reeling mill is preferably provided with a pair of positively driven skew-rollers 12 by which the tube is rolled over a mandrel 13, the head of which is preferably straight and of the same diameter throughout.

100

110

In this operation the tube is cross-rolled over the mandrel, thus practically eliminating scratches or internal grooves and giving it a smooth inner surface. At the same time the tube is straightened, though the essential function of the reeling mill is to eliminate the internal scratches and give an inner surface smooth enough for rapid and efficient drawing. After this cross-rolling the mandrel rod is drawn out of the tube by stripping mechanism indicated at 14, and rolls out 5 10 15 20 25 30 35 40 45 50 55 60 65 70 75 80 85 90 95 100 105 110 115 120 125 the expense for tools has been materially reduced. The reeling operation presents the same advantages in treating pierced billets without plug rolling, since such billets are rough and grooved on their interior.

The reeling mill may be of any desirable type so long as it performs the function of smoothing out the scores or grooves on the interior of the tube. The other parts of the apparatus may be varied widely without departing from my invention.

I claim:

1. The herein described improvement in the manufacture of seamless tubing, which consists in cross-rolling the tube over a mandrel to remove interior scores or grooves and to true up its gage, without materially reducing the thickness of its wall; substantially as described.

2. The herein described method of making seamless tubing which consists in rolling the pierced blank or billet in a plug-mill, then removing the blank and cross-rolling it over a mandrel to eliminate interior ridges or grooves and to true up the gage, without materially reducing the thickness of wall, and subsequently cold-drawing the tube; substantially as described.

3. The herein described method of making seamless tubing which consists in rolling the pierced billet or blank in a plug-mill, then removing the blank and cross-rolling it over a mandrel to smooth out the interior ridges, and to true up the gage, without materially changing the thickness of wall; substantially as described.

4. In the method of making seamless tubing, the steps which consist in elongating and thinning the pierced billet in a plug-mill, and then removing the hot blank and cross-rolling it over a plug, then removing the hot blank and rolling it over a mandrel to smooth out its interior without changing its gage, and then cold-drawing the blank, substantially as described.

In testimony whereof, I have hereunto set my hand.

JOHN H. NICHOLSON.
